[57] CLAIM

The ornamental design for a tire, as shown and described.

DESCRIPTION

FIG. 1 is a left side elevational view of a tire, showing my new design, the opposite side elevational view being a mirror image thereof;

FIG. 2 is a front elevational view thereof; and,

FIG. 3 is an enlarged fragmentary front-elevational view thereof.

The tread pattern is understood to be repeated uniformly throughout the circumference of the tire, as shown schematically by solid lines in FIGS. 1-2.
